UNITED STATES PATENT OFFICE.

JOSEPH HARRY GRUVER, OF BALTIMORE, MARYLAND.

SHEET-METAL BALL AND METHOD AND MEANS OF MAKING THE SAME.

1,278,915.

Specification of Letters Patent. Patented Sept. 17, 1918.

Application filed April 14, 1917, Serial No. 162,092. Renewed June 12, 1918. Serial No. 239,663.

To all whom it may concern:

Be it known that I, JOSEPH HARRY GRUVER, a citizen of the United States, and resident of Baltimore, Maryland, have invented 5 certain new and useful Improvements in Sheet-Metal Balls and Methods and Means of Making the Same, of which the following is a specification.

My invention relates to sheet metal balls 10 and presses for making the same and it consists in the features hereinafter described and particularly pointed out in the claims.

In the accompanying drawings;

Figure 1 shows a part of a die or press 15 for performing the first step in the formation of a cup-shaped blank which is afterward converted into the form of the complete ball.

Fig. 2 is a sectional view illustrating a 20 part of a press for performing a second operation on the blank.

Fig. 3 is a view of a tool with the blank 25 thereon, the said tool forming part of the mechanism for trimming and forming the edge of the blank ready for subsequent operations.

Fig. 3^a is an enlarged detail view.

Figs. 4 and 5 are views of portions of 30 presses for performing other successive operations upon the blank.

Fig. 6 is a view of a die which when substituted for the die shown in Fig. 5 will perform another step action on the blank to bring it more nearly spherical.

Fig. 7 is a view of a partly rolled blank 35 illustrating the opening as partly closed as a consequence of a rolling action on the blank.

Fig. 8 is a sectional view of the completed 40 ball after all the rolling operation has been performed thereon.

Fig. 9 illustrates a machine for performing a rolling action on the blank.

Fig. 10 illustrates the blank at different 45 stages of the operation.

Fig. 11 shows a holder for a blank to be trimmed.

Referring to Fig. 1 this is illustrative of 50 any suitable press that may be employed for shaping the blank up into cup-form, as shown at *a*, Fig. 10. After this first operation is performed the cup-shaped blank is subjected to the action of a press which may be of any suitable form, such as indicated 55 in Fig. 2. This elongates the blank into

the form shown at *b*, Fig. 10. This blank of elongated, cup-shaped form is now trimmed at its upper edge by means of a tool *A*, shown in Fig. 3, the blank being suitably held by clamps or jaws or any other 60 suitable form of holder and the said tool *A* having a portion to fit within the cup-shaped blank as shown at *x* to preserve its cup-shaped form and sustain it while the trimming operation is being performed. This 65 tool *A* is provided with a cutting edge at *y* which is adapted to trim and bevel the edge of the blank and preferably this beveling is done on the outer side of the upper edge, it being understood that the tool and blank 70 are given a relative rotary motion so that all parts of the edge of the blank are acted upon by the cutting edge of the tool *A*. There may be two of these cutting edges *y* on the tool so as to increase the production. 75 The blank after being taken from the tool *A* is in the form shown in Fig. 10 at *c*, from which it will be noticed that the upper edge of the blank is cut or trimmed on an incline extending upwardly and inwardly. 80

This edge having thus been trimmed is smooth throughout its entire extent, being free from jagged portions or indentations or split portions or scales, so that in the subsequent operation of turning the blank into 85 complete spherical form a complete and firm closure of the blank will result. The blank of the form *c* is next placed in a press, such as shown in Fig. 4, which results in reducing one end of the cup-like 90 blank to form a body with an inwardly turned wall or portion at *a'*, as indicated on the blank *d*, Fig. 10, and a substantially straight necked portion at *a''*, this neck portion terminating in the beveled edge at *a'*, 95 as above described.

The next step consists in turning inwardly the neck portion *a''* of the blank *d*, Fig. 10, so that the blank will then assume the form shown at *e*, Fig. 10. This form of the blank 100 results from the action of the press shown in Fig. 5. In the next step the blank assumes a form more nearly spherical as shown at *f*, Fig. 10, it having however a small opening at *z* shown in said figure. This form 105 of the blank results from the use of a die such as shown in Fig. 6, being substituted for the lower die shown in Fig. 5. It will be understood, however, that this die of Fig. 6 is intended to be used in a press like that 110

of Fig. 5 but separate therefrom. The blank of the form *f* shown in Fig. 10 is now annealed or softened to render it fit for the subsequent rolling operation. As just stated, 5 this blank has a small opening indicated at *a* and it will be observed that because of the inclined face of the edge of the blank this hole will be of a tapered form with the small diameter portion nearest the center 10 of the blank. A number of these blanks are now placed in grooves of the plates 2, and 15 3 of Fig. 9 and a rolling action is performed on the blanks by the relative rotation of these plates, said plates meanwhile being 20 pressed toward each other. This rolling action reduces the blanks slightly in diameter and partly closes the hole therein by reason of the rolling action causing the metal to work inwardly in the plane of the 25 spherical surface from all directions toward the center of the opening. The blank after the first rolling action is performed thereon assumes the form shown in Fig. 7, in which it will be noticed that the inner sharp corner 30 of the inclined end or edge face *a'* of the blank is brought together from all directions and the closing action of the opening has been started. After the first rolling action is completed the blanks are again annealed 35 to prepare them by softening for the second or final rolling action. This final rolling action is performed by an apparatus similar to that shown in Fig. 9 in which, however, the groove or grooves for receiving 40 the balls are of smaller diameter than the groove or grooves of the first rolling machine. The result of this second rolling action is illustrated in Fig. 8 showing in section the completed ball, in which it will be observed 45 that the metal had accumulated on the interior of the blank at the point where the opening is closed or in other words at the point where the circular edge of the blank is pressed from all directions toward the 50 center.

It will be observed by comparing Figs. 7 and 8 that the tapered recess in the blank of Fig. 7 is by the second rolling action filled up by crowding or swaging or flowing 55 the metal over into this inwardly tapered recess, the surplus metal flowing inwardly, as indicated at *a'*, Fig. 8, where it remains without detriment to the structure or use of the ball. By this method of operation 60 there will be no tendency for the metal to lap on the outer side of the ball in a thin layer and there will be no action resulting, such as closing the opening with a thin film of metal on the outside on the form of 65 a layer leaving the inner parts of the opening unfilled.

In the present process the first closing of the opening takes place at the innermost part of the wall or the meeting edges of the 65 blank and this is followed by a gradual fill-

ing up of the conical opening from the interior to the exterior of the ball, so that the final product will have its wall closed or united for the full thickness of the shell and furthermore, there will be extra thickness of metal at this point, due to the flowing inwardly of the metal as shown at *a'*, this adding strength to the ball here and effectually closing the opening throughout the thickness of the shell. 70

I do not limit myself to the employment of two machines for performing the rolling operations. 75

It will be observed that the trimming of the edge of the blank by the tool shown in Fig. 3 prepares the edge for uniting with opposite portions of said edge as the result of the rolling operation and all parts of the edge come together uniformly and at the same time closing the opening and as the 80 edge is free from split or serrated portions a uniform closing action will take place, metal at one side of the opening uniting with that at the other side at the same time that other portions of the edge unite with each 85 other. 90

The tool shown in Fig. 3 may be substituted by a tool of like form but adapted to provide a different form of the edge of the blank but in either case the tool not only 95 trims the edge to remove scale and serrated or split or jagged portions of said edge but thins or bevels the edge so that by a proper rolling action the opening will be solidly and uniformly closed. 100

As shown in Fig. 3^a the trimming tool may have its inclined cutting edge merge into a cutting edge at the top for trimming the extreme upper edge above the inclined or beveled face of the metal, this top trimming edge in the form shown being a curved continuation of the inclined cutting edge. 105

It will be seen from the above that the article produced is of one piece of sheet metal, without seam or joint, having an 110 isolated accumulation of metal on its interior at one spot, that is where the ball is finally closed, this accumulation of metal being composed of fibers of the original sheet metal mechanically knitted together, and being surrounded on all sides by the original metal in sheet form. 115

It will also be observed that at one stage of the process for making the ball the blank assumes approximately a spherical form 120 with an opening, the edge of which lies in one plane transverse to the axis of the opening.

What I claim is:

1. A hollow ball of one piece of metal 125 without seam or joint, formed from a single piece of sheet metal, said finished ball having an isolated accumulation of metal therein at the one spot where the ball is finally closed, said isolated accumulation being 130

made up of the fibers of the original metal mechanically knitted together and being surrounded on all sides by the original metal in sheet form, substantially as described.

5 2. The herein described process of making a one-piece sheet metal hollow ball consisting in making an approximately ball-like body with an opening, and forming it with the edge about said opening lying in one plane transverse to the axis of the opening and with the face of said edge inclined to the said axis, thus providing a tapering recess, and then rolling the body under pressure to spherical form until the opening is closed.

10 3. The herein described process of making a one-piece sheet metal hollow ball consisting in making an approximately ball-like body with an opening and forming it with the edge about said opening substantially circular and in one plane transverse to the axis of the opening and with the edge face inclined to said axis, thus providing an inwardly tapered recess and then rolling the body under pressure to spherical form until the opening is closed, substantially as described.

15 4. The herein described process of making a one-piece sheet metal hollow ball consisting in forming a blank of substantially cup-shape with a circular edge in one plane transverse to the cup's axis and inclined to the said axis, transforming said cup into a form approximating that of a ball and by rolling the blank under pressure bringing the inclined circular edge portion together to close the opening, substantially as described.

20 5. The herein described process of making a one-piece sheet metal hollow ball consisting in forming a blank of substantially cup-shape with the edge face inclined to the axis of the cup, transforming said cup into a form approximating that of the ball with an opening therein tapering inwardly as bounded by said inclined edge and by rolling the ball under pressure bringing the inclined edge portion together to close the opening.

25 6. The herein described method of making a one-piece sheet metal hollow ball consisting in first making a blank of cup-shape with a circular edge lying substantially in one plane transverse to the axis of the cup, trimming the circular edge to provide a surface inclined to the axis of the cup, then upsetting the blank to approximately spherical form and then rolling the blank to work the metal inwardly from all sides of the

opening to close the same, substantially as described.

7. The herein described method of making a one-piece sheet metal hollow ball consisting in first forming a blank of cup-shape with a circular edge lying in one plane transverse to the axis of the cup, trimming the circular edge of said cup-shaped blank while maintaining its edge upstanding in the plane of the side wall of the blank, then upsetting the blank into substantially spherical form and finally rolling it under pressure to work the metal of the edge inwardly from all sides of the opening to close the same, substantially as described.

10 8. The herein described method of making hollow sheet metal balls consisting in forming a cup-shaped blank with a circular edge lying in one plane transverse to the axis of the blank, trimming the circular edge of said blank while exerting pressure thereon in the direction parallel with the wall of the blank and toward the bottom thereof, then upsetting the blank into ball form, and rolling it under pressure to work the metal inwardly from all sides of the opening to close the same, substantially as described.

15 9. The herein described process of making a one-piece sheet metal hollow ball consisting in forming a blank of substantially cup-shape with the edge face inclined to the axis of the cup, transforming said cup into a form approximating that of the ball with a tapered opening therein as bounded by said inclined edge and then rolling the ball under pressure to mechanically knit together all parts of the inclined edge and until an accumulation of the metal occurs on the interior of the ball, substantially as described.

20 10. The herein described process of making a one-piece sheet metal hollow ball consisting in making a blank of approximately spherical form with an opening, the edge of which lies in one plane transverse to the axis of the opening and then rolling the ball under pressure to mechanically knit all parts of the edge together and until metal has accumulated on the interior of ball at the point of closure and projecting inwardly from the wall at the closure, substantially as described.

In testimony whereof, I affix my signature.

JOSEPH HARRY GRUVER,

Attest:
